AIR CONDITIONING UNIT

James L. Schucker, Royal Oak, Mich., assignor to General Motors Corporation, Dayton, Ohio, a corporation of Delaware

Application October 1, 1954, Serial No. 32,508

Term of patent 7 years

(Cl. D62—4)

Fig. 1

Fig. 2

Figure 1 is a perspective view showing the front, top and one side of an air conditioning unit embodying my new design; and

Figure 2 is a perspective view showing the rear, top and other side of said unit.

The dominant features of my design reside in the portions shown in full lines.

I claim:

The ornamental design for an air conditioning unit, as shown and described.
